UNITED STATES PATENT OFFICE.

NELLIE B. NOBLE, OF ITHACA, NEW YORK.

BEDSTEAD.

No. 846,236.

Specification of Letters Patent.

Patented March 5, 1907.

Application filed October 29, 1903. Renewed February 6, 1907. Serial No. 356,098.

To all whom it may concern:

Be it known that I, NELLIE B. NOBLE, of Ithaca, in the county of Tompkins and State of New York, have invented a certain new 5 and useful Bedstead, of which the following is a specification.

My invention has for its object the production of an attachment for beds which is particularly simple in construction, is especially applicable for use by physicians and nurses in the treatment of patients and invalids, and facilitates the ready removal from the bed of the person being treated; and to this end the invention consists in the 15 combinations and constructions hereinafter fully set forth, and pointed out in the claims.

In describing this invention reference is had to the accompanying drawing, in which like characters designate corresponding parts 20 in all the views.

Figure 1 is a perspective of a bed and a preferable embodiment of my attachment, partly broken away, operatively connected thereto. Fig. 2 is a plan view of the movable frame and the flexible supporting means or canvas sheet of my attachment, upright parts of the bed being indicated by dotted lines. Fig. 3 is a perspective view of the means shown in full lines in Fig. 2, a portion 25 of the rubber sheet being also illustrated. Figs. 4 and 5 are respectively plan and edge views of one end of the movable frame of my attachment. Figs. 6 and 7 are respectively side and end elevations of a portion of the 30 bedstead or supporting-frame equipped with my attachment. Fig. 8 is a plan of the detached rubber sheet.

My attachment is here illustrated as operatively connected to a metallic bedstead 1, having opposite separated uprights 2 3 at its 40 ends comprising vertical standards and upper and lower cross-rails extending between the same; but it will be understood that any other suitable supporting-frame may be used 45 instead of the bedstead 1.

The preferable embodiment of my invention comprises a movable frame 4, supporting means 5 6, and means for moving the frame 4 relatively to the bedstead or supporting-frame 1 and holding the frame 4 in its adjusted position. Said frame 4 and the supporting means 5 6 form, essentially, a movable support, upon which the patient or invalid lies.

55 The frame 4 usually comprises side bars 7 and outer and inner cross-bars 8 9 10 11, op-

posing surfaces of the extremities of the side bars being separated a greater distance than the end surfaces of the uprights 2 3 and normally arranged outside of said end surfaces 60 and the outer and inner cross-bars 8 9 10 11 being, respectively, in close proximity to the outer and inner surfaces of the uprights 2 3, the outer side surfaces of the inner cross-bars 10 11 being separated from the inner side surfaces 65 of the outer cross-bars 8 9. It is thus apparent that the frame 4 is provided with openings in its ends between the extremities of the side bars 7 and the cross-bars 8 9 10 11, which openings are of the full widths of the 70 uprights 2 3, and receive said uprights and permit vertical movement of the frame 4, and that the surfaces of the extremities of the side bars and the cross-bars forming the sides of said openings limit the movement of the 75 frame 4 longitudinally and transversely or in a horizontal plane relatively to the bedstead or supporting-frame. Moreover, the portions of the movable frame, as the outer cross-bars and the ends of the side bars, projecting beyond the contiguous outer surfaces 80 of the bedstead, form hand-engaging means which facilitate the ready engagement of the frame 4 and the removal of said frame as a whole from the bedstead 1. One of the inner cross-bars, as 11, is generally journaled in the adjacent extremities of the side bars 7, is movable endwise against the action of a spring 12, and is provided with a clutch-section 13, which engages with the clutch-section 85 90 14, fixed to one of the side bars 7. The cross-bar 11 may be revolved by a detachable handpiece or crank, (not illustrated,) is free to move endwise against the action of the spring 12 to permit movement of the clutch-section 13 relatively to the clutch-section 14, and is held in its adjusted position by the engagement of said clutch-sections 13 14. The passage of the movable frame 4 through doorways may be facilitated by providing 95 100 intermediate portions of the cross-bars 8 9 10 11 with hinges 15 of any desirable construction, unnecessary to describe herein, capable of being locked from operation, so that the cross-bars may normally be as rigid 105 as though unprovided with hinges; but said hinges 15 may be dispensed with, if desired. As best seen in Figs. 1, 2, and 3, the supporting means 5 consists of a sheet of canvas or other suitable flexible material, having its 110 sides provided with straps or other desirable fastening means for securing said sheet to

the side bars 7 and permitting the same to slide lengthwise of said bars. One end of the supporting means 5 is provided with straps or fastening means secured to the inner cross-bar 10, and the other end thereof is suitably fastened to the cross-bar 11, which is revolved in opposite directions for tightening and loosening the supporting means 5. The supporting means 6 is composed of rubber or other waterproof material and is also provided with straps or other suitable means for securing the same to members of the frame 4. In the illustrated construction of my invention the ends of the supporting means 5 6 are provided with securing-straps engaged with the outer cross-bars 8 9 of the frame 4; but it will be understood that these securing-straps may either be dispensed with or that the same must be disengaged from the cross-bars 8 9 whenever it is desired to remove the support for the patient or invalid from a supporting-frame 1 having top cross-bars, as shown herein. The supporting means 6 preferably comprises a sheet or body portion having its longitudinal edges provided with inflatable portions which constitute marginal flanges and a substantially triangular-shaped pocket, from the apex of which an exit-conduit 18 leads. This pocket preferably includes a flat upper wall arranged in a plane coincident with the tops of the marginal flanges and a bottom wall substantially coincident with the body portion of the sheet and preferably formed by a continuation of the latter. The exit-conduit 18 may be provided with a clamp 19 for shutting off or permitting flow therethrough.

As best seen in Fig. 1, the means for varying the position of the movable support for the patient or invalid relatively to the bedstead or supporting-frame consists of independently-revoluble drums 20, journaled in said bedstead or supporting-frame, pulleys 21, detachably secured to the upper cross-rails of the uprights 2 3, and flexible connections 22, having corresponding ends connected to the drums 20, their intermediate portions passed between the cross-bars 8 9 10 11 and over the pulleys 21 and their other ends detachably connected to the frame. The drums 20 may be revolved by any desirable handpieces detachably engaged therewith and may be held in their adjusted position by any suitable means, as ratchet-wheels 23 and pawls 24.

In the use of my attachment the ends of the support for the patient or invalid may be raised or lowered independently relatively to the bedstead or supporting-frame 1 and may be readily detached from the flexible connections 22, whereupon the support as a whole and the patient lying thereupon may be easily raised above the bedstead or supporting-frame and then removed to an operating-room or other desired place. My at-

tachment is particularly applicable for use in maternity cases or for convenience in bathing and immersion or when irrigation is necessary. Moreover, in some cases with a patient or invalid lying on the bed proper the movable frame 4 may be placed in position and the canvas sheet arranged beneath the patient or invalid and then fastened to the movable frame, whereupon the person may be raised as desired for facilitating changing of the bedclothes, airing of the bed, or the passage of a cooling current of air beneath the patient.

The construction and operation of my bedstead will now be readily understood upon reference to the foregoing description and the accompanying drawing, and it will be apparent to those skilled in the art that more or less change may be made in the component parts thereof without departing from the spirit of my invention.

Having thus fully described my invention, what I claim as new, and desire to secure by Letters Patent, is—

1. The combination of a bedstead having uprights at its ends and a support for a patient, said support being supported by the bedstead and removable as a whole therefrom and being provided with means coacting with the uprights for limiting the movement of the support longitudinally and laterally, substantially as and for the purpose specified.

2. The combination of a bedstead having uprights at its ends and a support for a patient, said support being connected to the bedstead and separable as a whole therefrom, and being provided at its opposite ends with openings, the inner side walls of the openings being opposed to opposite side surfaces of the uprights and the inner end walls of the openings being opposed to opposite end surfaces of the uprights, substantially as and for the purpose described.

3. The combination with a metallic bedstead having head and foot uprights comprising vertically-arranged standards and upper and lower cross-rails; of a movable support comprising side bars, end bars arranged within the upright standards, supporting means secured at its edges to the side and end bars, and additional end bars arranged to the outside of the uprights and connected to the side bars; drums provided on the bedstead; pulleys supported by the upper cross-rails of the uprights; and flexible connections having corresponding ends connected to the drums, their intermediate portions passing between the first-named end bars of the support and the additional end bars and passing over the pulleys and their other ends connected to the additional end bars, substantially as described.

4. The combination of a supporting-frame, a movable frame comprising side

bars, outer cross-bars, inner cross-bars having their outer surfaces separated from the inner side surfaces of the outer cross-bars, one of the inner cross-bars being revoluble 5 relatively to the side bars, clutch-sections provided on the revoluble bar and one of the other bars, a spring for engaging the clutch-sections, supporting means secured to a fixed part of the movable frame and to the 10 revoluble inner cross-bar, and means connected to the frames for holding the movable frame in its adjusted position, substantially as described.

5. The combination of a supporting-frame, a movable frame comprising side bars and cross-bars, one of the bars being revoluble and movable endwise relatively to the others, clutch-sections provided on the revoluble bar and one of the other bars, a 15 spring for engaging the clutch-sections, supporting means secured to a fixed part of the movable frame and to the revoluble bar, and means connected to the frames for holding the movable frame in its adjusted position, 20 substantially as and for the purpose described.

6. The combination of a supporting-frame, a movable frame comprising side bars, outer cross-bars, inner cross-bars having their outer side surfaces separated from the inner side surfaces of the outer cross-bars, one of the inner cross-bars being revoluble 25 relatively to the side bars means for holding the revoluble inner cross-bar in its adjusted 30 position, supporting means secured to a fixed part of the movable frame and to the revoluble inner cross-bar, and means connected to the frames for holding the movable frame in its adjusted position, substantially as and 35 for the purpose specified.

7. The combination of a supporting-frame having separated uprights, a movable frame comprising side bars having opposing surfaces of their extremities at the outside of 45 the ends of the uprights, and outer and inner cross-bars at opposite sides of said uprights, supporting means secured to the movable frame, and means connected to the frames for holding the movable frame in its adjusted 50 position, substantially as and for the purpose set forth.

8. The combination of a bedstead, a frame movable relatively to the bedstead separable therefrom and including movable means, and supporting means secured to a 55 fixed part of the frame and to said movable means, whereby said supporting means may be tightened and loosened through the manipulation of said movable means.

9. The combination of a supporting-frame 60 having separated uprights, a movable frame comprising side bars having opposing surfaces of their extremities at the outside of the ends of the uprights, and outer and inner cross-bars at opposite sides of the uprights, 65 said movable frame being connected to the supporting-frame and separable therefrom, and supporting means detachably connected to the side bars and the inner cross-bars of the frame, substantially as and for the purpose set forth.

10. The combination of a bedstead, a frame movable relatively to the bedstead, and a waterproof supporting means detachably secured to the frame and provided with 75 raised inflatable side portions, a receiving-pocket at one end and an exit-conduit, substantially as and for the purpose specified.

11. The combination of a supporting-frame having separated uprights, a movable 80 frame comprising side bars having their extremities at the outside of the ends of the uprights, and outer and inner cross-bars at opposite sides of the uprights, said movable frame being connected to the supporting-frame and separable therefrom, supporting means detachably connected to members of the movable frame, and waterproof supporting means mounted on the former supporting means and also detachably connected to 85 members of the movable frame, substantially as and for the purpose set forth.

In testimony whereof I have hereunto signed my name, in the presence of two attesting witnesses, at Ithaca, in the county of 95 Tompkins, in the State of New York, this the 27th day of October, 1903.
